HAIR WAVING DEVICE

Alice Davis, Adams, Mass.

Application September 24, 1940, Serial No. 358,096

2 Claims. (Cl. 132—33)

This invention relates to devices for the permanent waving of human hair and more particularly to devices for imparting waves in which both the "spiral" and "Croquignole" types of curls are combined.

There is an insistent demand for such combination waves, it being generally considered that the most satisfactory results are obtained when the spiral form of wave is applied to the inner parts of the strands of hair, that is, the portions lying closer to the scalp, while the Croquignole type of curl is imparted to the outer ends of the strands. Expedients thus far suggested for obtaining the desired result have been subject to certain disadvantages. Either they involved the use of complicated and cumbersome apparatus, unsuited to the working conditions prevailing in the dressing of hair, or separate operations and different curling instruments have been required.

It is the main object of the invention to provide a simple and effective hair waving instrument of compact unitary form which will impart both spiral and Croquignole curls to a strand of hair in a single operation.

A further object is to provide a hair waving appliance comprising a single curling rod which lends itself to the production of a variety of combinations of spiral and Croquignole curls. Individual taste requires sometimes more and sometimes less of the Croquignole type of curling in combination with varying amounts of spiral waving. It is an important feature of the invention that one and the same curling rod may be employed to produce a variety of effects of the kind indicated by simple variations of the manner of using it.

Another object is to improve the results obtainable by so-called "machineless" waving while substantially reducing the time required for heating the hair to set the waves.

Other objects and advantages of the invention will appear in the following description of a preferred embodiment thereof shown in the accompanying drawings, wherein:

Fig. 1 is a plan view of the device, assembled,

Fig. 2 is a dropped elevation showing the curling rod and its holder separated,

Fig. 3 is an end view of the curling rod,

Fig. 4 is an enlarged broken-off view of the curling rod, partly in longitudinal section,

Fig. 5 is a transverse section on the line 5—5 of Fig. 4,

Fig. 6 is a broken-off longitudinal section hereinafter compared with Fig. 4,

Figs. 7 and 8 are views showing two ways of 55

using the device to make combined Croquignole and spiral curls.

The hair waving device shown in the drawings consists in general of a hair clamp or protector and a curling rod, the former serving as a supporting frame for the latter.

The hair clamp comprises rigid bars 1, 2 hinged together at 3 and provided at their outer ends with hooks 4 and 5. A fastening link composed of plates 6 and 7 and spacer pins 8 and 9, is more or less permanently engaged at one end with hook 4 which is deeply slotted. The other end of the fastening link is adapted to be readily engaged or disengaged with the shallow hook 5 on bar 2 and an eccentric lever 10 pivoted on pin 9 cooperates in opening and closing the clamp in known manner. Bars 1 and 2 are preferably covered with sleeves 11 which may be made of rubber to provide a soft gripping surface. At either end of the clamp there are yokes 12 and 13 to serve as supports for the ends of the curling rod, as hereinafter described. Yoke 12 projects upwardly from the hooked portion 14 of bar 1 and yoke 13 is rigidly secured to upper plate 6 of the fastening link. This clamp, as thus far described, is not substantially different from others known to the art.

Referring now to the curling rod 15, it will be seen that it is provided with a spiral rib or worm 16 of sufficiently high relief to provide an adequate channel in which to form and hold a spirally curled tress of hair. Beyond the ends of the worm the rod 15 is left smooth for a short space to provide for formation of any desired number of Croquignole turns of the tress of hair, that is, turns which do not progress axially but wind successively one upon another.

On the right end of rod 15 there is a collar 17 having a diagonal notch 18 in which the end of the strand of hair may be caught to prevent unwinding of the coil. The end of the rod is squared to receive a wing nut 19.

At the left end rod 15 terminates in a cup-shaped head 20 in which there may be seated a removable end plug 21. The inner end of plug 21 is slotted at 22 to receive the end of a coiled spring 23 (Fig. 4) or spring 24 (Fig. 6), these springs being oppositely coiled and interchangeable. It will be observed that the diameter of these springs is such as to produce a snug fit with hollow head 20 and any relative rotary movement between the spring and head in one direction will tend to expand the spring, thereby increasing the frictional resistance to such relative motion, whereas movement in the other

direction will be relatively free. In other words, the springs 23 and 24 constitute one-way clutches or brakes and, being oppositely wound, the springs provide means for selectively locking the curling rod 15 against rotary motion relative to plug 21 in either the clockwise or anti-clockwise directions.

When the rod is assembled with the clamping support previously described, the squared end of plug 21 will be non-rotatably seated in yoke 13 whereas the other end of the rod is rotatably seated in yoke 12. A clamp or clip 25 is pivotally secured to head 20 for a purpose to be described.

The operation of the device, that is, the manner in which it may be employed to produce combination spiral and Croquignole waves, will now be described. The extreme end of a strand of hair is first engaged under clamp 25, the curling rod at the beginning of the operation being detached from the clamp if desired. The strand is then given several turns of Croquignole or superimposed windings on the smooth portion of the rod and overlying clamp 25. Having completed a sufficient number of turns to produce the desired amount of Croquignole effect, the strand is led into the spiral groove formed by worm 16 and spiral winding is thereupon proceeded with. The curling operations just described are preferably performed by the operator's fingers on the detached rod. The rod is then seated in the yokes on the clamp which has previously been clamped upon the strand of hair near the scalp. Rod 15 is thereupon turned in counter-clockwise direction by means of wing nut 19 which imparts tightness to the curl in both its Croquignole and spiral portions. With the method just described spring 24 (Fig. 6) is used to allow the clockwise tightening rotation of the rod while preventing rotation of the rod in the opposite direction which would unwind the curl.

A second procedure of curling may be employed, in which the spiral curl is formed first, beginning near the scalp, and a small Croquignole is added at the end of the strand. The strand is applied to the worm portion of the curling rod (Fig. 8), at any desired point, determined by the length of the strand and the relative amounts of spiral and Croquignole curling desired. Spiral winding is carried out to the 50

end of the worm and the short remaining end of the strand is then wound upon itself in Croquignole fashion. A piece of crepe wool may then be blended into the extreme end of the strand and led into notch 18 to anchor the curl at that end. The clamping support is then applied to the strand near the scalp and the curling rod seated therein. Next, the curl is tightened by turning the rod in clockwise direction. In this operation the plug carries spring 23 (Fig. 4) which permits the rod to rotate in the clockwise direction but prevents counter-clockwise rotation.

When the combination curl is completed, heat is applied to set the curl. For this purpose chemical heating pads may be employed instead of the relatively expensive and time-consuming electrical or "machine" heaters. Heating pads, although preferred for economical and time-saving reasons, have not heretofore produced long-lasting waves because the amount of heat delivered by such pads is insufficient to thoroughly penetrate the thick mass of hair produced by previous waving methods, in which five or six inch strands are wound in the Croquignole form. According to the present invention, a relatively thin mass of hair, produced by a few turns of Croquignole winding, say, one to one and a half inches of strand, is subjected to heating. The heat penetrates to the very end of the strand and "machineless" waving is made practicable for the first time.

I claim:

1. A hair waving device comprising a curling rod having a worm on its periphery, said worm stopping short of each end of the rod to leave an uninterrupted winding surface at each end of said worm.

2. A hair waving device comprising in combination a curling rod having a worm on its periphery, said worm stopping short of each end of the rod to leave an uninterrupted winding surface at each end of said worm, means adjacent each of said uninterrupted winding surfaces for anchoring a strand of hair, a frame rotatably supporting said rod, and means for selectively preventing rotation of said rod in either, but only one, direction.

ALICE DAVIS.
